(57) **CLAIM**

The ornamental design for a one-compartment container, as shown and described.

DESCRIPTION

FIG. 1 is a top plan view of a one-compartment container, showing our new design;

FIG. 2 is a front elevational view thereof;

FIG. 3 is a left-side elevational view thereof, the right-side view being a mirror image of FIG. 3;

FIG. 4 is a rear elevational view thereof;

FIG. 5 is a bottom plan view thereof;

FIG. 6 is a perspective view thereof;

FIG. 7 is a perspective view thereof, in a partially opened condition; and,

FIG. 8 is a plan view of the interior thereof, in a fully opened condition.

1 Claim, 8 Drawing Sheets
